(57) CLAIM

The ornamental design for a portable massager, as shown and described.

DESCRIPTION

FIG. 1 is a front perspective view of a portable massager, showing my new design;

FIG. 2 is a front view thereof;

FIG. 3 is a back view thereof;

FIG. 4 is a left-side view thereof;

FIG. 5 is a right-side view thereof;

FIG. 6 is a bottom view thereof;

FIG. 7 is a top view thereof; and,

FIG. 8 is a rear perspective view thereof.

The broken lines in the drawings are for the purpose of illustrating portions of the portable massager, which form no part of the claimed design.
